FOREIGN PATENT DOCUMENTS

WO 2011038016 A2 3/2011

Primary Examiner — Nathan M Johnston*(74) Attorney, Agent, or Firm* — Fitch, Even, Tabin & Flannery LLP(57) **CLAIM**

The ornamental design for a paper towel dispenser, as shown and described.

DESCRIPTION

FIG. 1 is a top, front perspective view of a paper towel dispenser in accordance with our new design, shown in a closed position;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, front perspective view thereof in an exploded, open position;

FIG. 9 is a front elevation view thereof in an exploded, open position;

FIG. 10 is a rear elevation view thereof in an exploded, open position;

FIG. 11 is a left side elevation view thereof in an exploded, open position;

FIG. 12 is a right side elevation view thereof in an exploded, open position;

FIG. 13 is a top plan view thereof; and,

FIG. 14 is a bottom plan view thereof.

The broken lines shown in the figures represent portions of the paper towel dispenser that form no part of the claimed design.

1 Claim, 11 Drawing Sheets(56)
